UNITED STATES PATENT OFFICE.

HENRY E. J. HARTMANN, OF KANSAS CITY, MISSOURI.

PAPER BAG.

No. 866,275.

Specification of Letters Patent.

Patented Sept. 17, 1907.

Application filed July 16, 1906. Serial No. 326,423.

To all whom it may concern:

Be it known that I, HENRY E. J. HARTMANN, a citizen of the United States, residing at Kansas City, in the county of Jackson and State of Missouri, have invented certain new and useful Improvements in Paper Bags, of which the following is a specification.

My invention relates to improvements in paper bags.

The object of my invention is to provide a paper bag with means by which it may be readily carried when filled.

My invention provides a paper bag the sides of which are perforated adjacent the top of the bag, the perforations being disposed, when the bag is folded flatwise so as to form two holes through the folded bag, through which holes is adapted to be inserted a loop of flexible material which will serve as a handle.

My invention provides further novel means for reinforcing or strengthening the bag adjacent the perforations for the purpose of preventing tearing of the sides of the bag by the flexible handle.

Other novel features of my invention are herein-after fully described and claimed.

In the accompanying drawings illustrating my invention, Figure 1 is a perspective view of a paper bag constructed in accordance with the principles of my invention, the bag being shown in the open position. Fig. 2 is a perspective view of the upper end of the improved paper bag shown in the closed position. Fig. 3 is a side view of one side of the bag having attached thereto the reinforcing string. Fig. 4 is a vertical sectional enlarged view of the upper end of the bag, the section being taken through one of the holes having the string handle inserted therethrough, the bag being shown closed. Fig. 5 is a side view of one of the reinforcing sheets. Fig. 6 is a perspective view of the lower end of part of the bag, looking at the underside.

Similar characters of reference denote similar parts. The paper bag comprises a rectangular body having two outer sides 1, two foldable sides 2 and the foldable bottom 3. The sides are provided each adjacent the upper end of the bag with two perforations 4. The sides 2 are provided with central vertical creases 5, each of which branches adjacent its lower end into two creases 6 which lead to the two adjacent corners of the bottom 3, the middle portion of the bottom 3 being creased at 7. The disposition of the holes 4 is such that when the bag is folded flatwise, as shown in Fig. 2 with the sides 2 and bottom 3 between the outer sides 1 the perforations will form two holes

adapted to receive therethrough a loop of flexible material, such as a string having the ends tied, and forming a handle 8 by which the filled bag may be carried. To prevent the handle 8 tearing the sides, two of the 55 sides, as for instance the outer sides 1 are reinforced above the holes 4. Preferably this reinforcing comprises two sheets of reinforcing material 9 secured to the sides 1 respectively, each sheet having two perforations registering with the perforations in the side 60 to which the sheet is attached. The sheets 9 may be of any desired shapes and sizes and may be secured to the sides by paste. To further strengthen the sides around the perforations 4 two strings 10 are disposed intermediate the sheets 9 and the sides 1, the ends of 65 each string 10 preferably encircling respectively the holes 4 in the side 1 to which the string is affixed.

In the manufacture of the bags, the sheets 9 and strings 10 may be affixed to the sides before the sides are perforated. The bag may then be folded flatwise 70 as shown in Fig. 2 and the perforations 4 made by cutting holes through the folded bag in the spaces encircled by the ends of the strings 10. The strings 8 may then be inserted, while the bag is folded, through the holes so formed, the ends of the string being tied 75 together, thus forming a loop which serves as a handle. The length of the string forming the handle 8 should be sufficient to permit the bag to be fully opened for the insertion and removal of the contents. One of the outer sides 1 may be provided in its upper edge 80 with a notch 11 which permits the ready grasping of the opposite side 1 whereby the sides 1 may be separated from each other.

My invention may be modified in different ways within the scope of the appended claims without departing from its spirit.

Having thus described my invention, what I claim and desire to secure by Letters Patent, is:—

1. A rectangular foldable paper bag having two perforations through each side, two opposite sides and the bottom 90 of the bag being creased so as to be inwardly folded between the other two sides, the perforations in each folded side, when the bag is folded flatwise, registering with each other and with the adjacent perforations of the outer sides, thus forming two holes extending through the folded bag, 95 two of the sides having secured transversely to each a string the ends of which encircle the perforations of the side to which the string is secured, and a loop of flexible material extending through said holes and forming a handle. 100

2. A rectangular foldable paper bag having two perforations through each side, two opposite sides and the bottom of the bag being creased so as to be inwardly folded between the other two sides, the perforations in each

folded side, when the bag is folded flatwise, registering with each other and with the adjacent perforations of the outer sides, thus forming two holes extending through the folded bag, each of two of the sides having secured thereto 5 a sheet of reinforcing material having perforations registering with the perforations of the side to which said material is attached, two strings intermediate respectively the two said sheets and the sides to which the sheets are attached, the ends of each of said strings encircling the

adjacent perforations, and a loop of flexible material extending through said holes and forming a handle.

In testimony whereof I affix my signature in presence of two witnesses.

HENRY E. J. HARTMANN.
